FIG. 4

FIG. 3

FIGURE 1 is a side elevational view of a sanctuary lamp showing my new design.

FIGURE 2 is a side elevational view of the lamp looking to the left, FIGURES 1 and 5.

FIGURE 3 is an elevational view of the side opposite that shown in FIGURE 1, the view looking to the left in FIGURES 1 and 5.

FIGURE 4 is an elevational view of the side opposite to that shown in FIGURE 1, the view looking downward in FIGURE 5.

FIGURE 5 is an enlarged sectional view taken on line 5—5, FIGURE 1.

The outer surface of the side panels surrounding the motifs, shown in FIGURES 1, 2 and 3, is formed with a multiplicity of small pyramids which are rounded at the vertex, the entire side panel in FIGURE 4 is of that form.

I claim:

The ornamental design for sanctuary lamp, as and described.
